UNITED STATES PATENT OFFICE.

ALEXANDER BOYNTON, OF SAN ANTONIO, TEXAS.

POLISHED ROD ROTATOR.

Application filed June 19, 1926. Serial No. 117,193.

The invention forming the subject matter of this application is in the nature of a polished rod rotator especially adapted for use in connection with well pumping equipment and an important object is to provide for a limited rotation of the plunger rod on each down stroke thereof to distribute wear, keep the stuffing box and other parts in round, and provide for the increased life 10 of the equipment.

A further object is to provide a polished rod rotor having simple means whereby the rods are prevented from being twisted in two should the cups or plunger stick.

Another aim is to provide a polished rod rotator which may be applied to a polished rod and a beam without altering the construction of these parts and which is provided with simple means to permit of the 20 pulling of the rods without entirely detaching or dismantling the rotator whereby the employment of the improved rotator is not accompanied by time consuming operations as are so many attachments in the industry.

A further and equally important object is to provide an intermittent polished rod rotator having simple means whereby the throw or zone of action of the same may be varied for operation under a variety of conditions, and which will have an intermittent tightening effect on the joints of the rods to keep the rods tight.

Other objects and advantages will be apparent during the course of the following 35 description.

In the accompanying drawings forming a part of this application and in which like numerals are employed to designate like parts throughout the same,

Figure 1 is a side elevation of the improved polished rod rotator applied;

Figure 2 is a similar view taken at substantially right angles to Figure 1;

Figure 3 is a vertical sectional view 45 through that part of the improved rotator adapted for application to the polished rod;

Figure 4 is a horizontal sectional view taken on line 4—4 of Figure 3.

In the drawings, the numeral 10 designates a beam of conventional or other design and the numeral 11 designates a polished rod adapted to extend through a polished rod trunnion 12 as clearly shown in Figures 1 and 2. Figure 2 probably best 50 illustrates that the trunnion set screw 14

may be engaged with the polished rod to firmly attach the polished rod to the trunnion, but at this point it is important to note that the successful operation of the improved rotor shown in Figures 1 to 4, inclusive, is dependent on the loosening of the screw 14 before the well is pumped with the aid of the improved rotor. As previously stated, the invention is in the nature of a device designed to impart intermittent rotation to the rod and if the set screw 14 were in locking engagement with the polished rod, this would be impossible since the trunnion 12 is mounted on a saddle 15 secured to the beam.

That part of the improved rotator which is applied directly to the polished rod is best shown in Figure 3 wherein the body of the rotator is designated by the numeral 16 and consists of a more or less tubular body 60 having upper and lower set screws 18 to clamp the body securely to the polished rod. The clamping action of the set screws 18 may be supplemented by a longitudinally 65 split nipple threaded into one end of the body 16.

In carrying out the invention, the intermediate portion of the body is externally enlarged and is provided with an annular series of ratchet teeth as shown in Figure 4, which ratchet teeth are engaged by a spring actuated dog 19. Figure 4 also illustrates that the dog 19 is movable within a radially extending housing 20 on a shell or annular attaching member 22. The housing 20 also encloses the shank 24 of the dog and a coil spring 26 is confined between the major portion of the dog and the rear end of the housing. The function of the spring 26 is obviously to urge the dog 19 into engagement with the ratchet teeth on the adjacent portion of the body. Therefore, turning of the annular attaching portion 22 will result in turning of the body in the proper direction. However, on the return or backward movement of the annular body 22 no 70 rotative force will be applied to the body 16.

Referring now to Figure 3 it will be seen 75 that the annular attaching body or shell 22 rests upon and turns upon an annular supporting flange or shoulder 28 formed integral with the body so that the dog 19 is maintained in constant operative relation to the ratchet teeth. The dog 19 normally 80 extends beyond the inner surface of the 85

shell 22 and to permit of the application of the body 22 to the main tubular body 16 the exteriorly arranged rear terminal portion of the shank 24 is gripped by a pair of pliers or other suitable tool to retract the dog 19 whereupon the shell or annular attaching member 22 may be easily slipped into place.

Also when it is desired to detach the annular shell 22 from the body 16 it is merely necessary to retract the dog 19 with the aid of a pair of pliers or the like and then slip the shell off the body as will be obvious.

The rotator body 16 rests upon a washer 30 and the washer in turn is mounted on and is positioned within a cup-shaped member 32, the cup being adapted to receive a suitable lubricant to reduce friction between the rotator and the polished rod trunnion.

Referring now to the actuating means by which intermittent rotation is imparted to the polished rod, it is pointed out that the shell or attaching annular member 22 is provided opposite the housing 20 with a lateral projection 35 having a vertical opening to adjustably receive an arm 36. Figure 4 plainly illustrates that a set screw 37 may be employed to secure the arm 36 in an adjusted position with respect to the lateral projection 35. The arm 36 is made adjustable to avoid the necessity of positioning the rotor a substantial distance above the polished rod trunnion. If the rotor is positioned too high upon the polished rod, the polished rod is apt to bend under the strain incident to the intermittent operation of the rotor. To avoid such bending it is desirable that the rotating mechanism be kept well down upon the polished rod trunnion.

The upper portion of the arm 36 has a laterally extending opening to rotatably and slidably receive a connecting shaft or pin 38 having a substantially oval-shaped head 39.

The head 39 is movable within a vertically positioned, transversely curved actuator 42 rigidly secured to and preferably formed integral with a bracket 43. Figure 1 clearly illustrates that the bracket 43 extends upwardly from an attaching base 44 secured to the beam by U bolts 46.

Assuming the well is on the pump and it is desired to apply the rotor, the usual polished rod clamp is first removed. The set screw 14 is tightened to bear the weight of the rods while the rotor assembly is being applied, and, as previously stated, after the rotor has been applied and rigidly secured to the polished rod the set screw 14 is loosened so that the desired intermittent rotation may be imparted to the rods.

The next step is to apply the washer 30 and the cup 32 and then apply the body 16 with the elements connected thereto.

With the body 16 and associated elements

thus secured to the polished rod the arm 36 is extended through the opening in the member 35 and the more or less oval-shaped head 39 is received in the transversely curved actuator 42. The bracket 43 of the actuator 42 is securely attached to the beam so movement of the beam will be imparted to the actuator 42.

In finally adjusting the rotor, care must be taken to loosen the polished rod trunnion lock screw 14 and to position the laterally projecting housing 20 at right angles to the beam when the beam is midway between the upper and lower extreme positions so that exactly the right movement will be imparted to the polished rod. That is to say, when the rotor is properly adjusted the laterally projecting housing 20 will be at right angles to the beam when the beam is midway between the ends of its travel.

The rocking of the beam will be accompanied by a similar movement of the actuator head 39 so that when the beam is moving downwardly the head 39 will be moved forwardly whereby the shell 22 and the spring actuated dog 19 carried thereby will be turned in a clockwise direction. When the shell 22 and the spring actuated dog are thus moved in a clockwise direction the body 16 of the rotor will be similarly turned to bring about the turning of the polished rod, the sucker rods connected thereto, and the cups. As the arm 36 advances on the descent of the beam it will partake of a slight arcuate movement about the axis of the rotor and hence the upper portion of the arm 36 moves lengthwise of the shaft 38. As the beam approaches the end of its travel in either direction the actuator 42 is naturally in a tilted position, but this will not affect the arm 36 as the oval-shaped head is movable with the actuator. It is thus seen that the head is not only rotatably connected to the arm 36, but is also slidably connected thereto. Of course, the rocking of the beam also causes the movement of the head 39 lengthwise of the actuator.

Should it be desired to pull the rods it is merely necessary to detach the arm 36 whereby the connection between the bracket 35 and that part of the rotor which is connected to the polished rod is broken. The polished rod may now be removed and laid in the derrick frame or on the ground along with the sucker rods which are later pulled. When it is desired to re-install the rods and again mount the polished rod this is done without interference by the rotator. It is a simple matter to reconnect the actuator 42 to the lateral projection 35 through the medium of the arm 36 so that the well is again ready for pumping.

When the rotator is employed below the beam a polished rod clamp 168 is employed in the usual manner.

The employment of a polished rod rotator constructed in accordance with this invention avoids wear on any particular portion of the equipment. In case a grain of sand or other foreign substance is lodged on one of the cups the working barrel will not be scored and the intermittent turning of the cups will distribute the wear so that the well may operate for a longer period than would otherwise be possible without pulling the rods. Also, the intermittent turning of the rods in a clockwise direction maintains the joints tight and thereby avoids parting of the joints so objectionable in the operation of pumping wells. Another feature of the invention resides in the fact that wear on the stuffing box is uniformly distributed and consequently leaks are avoided.

By thus distributing the wear and avoiding the formation of squirt grooves or jets, cutting of the oil is overcome. It is well known that the use of defective cups, etc., emulsifies the oil to a certain extent so that its sale value is lessened. By the employment of this invention emulsification of the oil while being pumped is prevented.

During the normal operation of the pumping equipment and the accessory forming the subject of this application the rods are turned in a clockwise direction on each down stroke of the pump. This turning is, of course, under the influence of the rotor, but should the cups or plunger become stuck in the working barrel, a back strain will be built up in the rods and this back strain will cause the oscillating part of the rotor to move back with the actuator during the return of the actuator to an operative position from where it may again turn the rods in a clockwise direction. It will thus be seen that the rotor will be prevented from twisting the rods to the breaking point. The action of the rotor is positive until the back strain caused by sticking of the cups or plunger exceeds a predetermined point and then additional twisting of the rods is prevented, this arrangement or clutch action constituting one of the main safety features of the invention.

Having thus described the invention, what is claimed is:

1. A polished rod rotator comprising a body having means whereby the same may be connected to a polished rod, an intermittent turning device associated with the body,

an arm connected to the turning device, a member rotatably and slidably connected to the arm, and an actuator to which said member is slidably connected.

2. A polished rod rotor comprising a body 60 having means whereby the same may be connected to a polished rod, an intermittent turning device associated with the body, an arm connected to the turning device, a member rotatably and slidably connected to the 65 arm, an actuator to which said member is slidably connected, and a bracket supporting the actuator and having means whereby the same may be secured to a beam.

3. A polished rod rotor comprising a body 70 having means whereby the same may be connected to a polished rod, an intermittent turning device associated with the body, an arm connected to the turning device, a member rotatably and slidably connected to the 75 arm, an actuator to which said member is slidably connected, and a bracket supporting the actuator and having means whereby the same may be secured to a beam, said actuator being curved transversely and said member being reduced toward the ends thereof whereby the same may move within the actuator.

4. In a device of the character described an actuator having means whereby the same 85 may be rigidly secured to a beam, a connecting member having a head movably positioned within the actuator, an arm slidably and rotatably connected to said member, and a polished rod rotating device having means 90 whereby the same may be moved about the axis of a polished rod and having rigid connection with said arm, the slidable connection between said arm and said member permitting of the movement of the rotating 95 device about the axis of the rod.

5. A polished rod rotating device comprising a polished rod rotating unit having a lateral projection, an arm rigidly and adjustably connected to said projection and being provided with an opening, a connecting member slidably and rotatably extended through said opening and being provided with an oval-shaped head, and a transversely curved actuator movably receiving said head 100 and being provided with means whereby the same may be secured to a beam.

In testimony whereof I affix my signature.

ALEXANDER BOYNTON.
